WALTER H. OGDEN, OF CLEVELAND, OHIO, ASSIGNOR TO R. HOE & CO., INC., OF NEW YORK, N. Y., A CORPORATION OF NEW YORK

WEB-ROLL-CONTROL MECHANISM

Application filed November 19, 1926. Serial No. 149,331.

This invention relates to certain improvements in web controlling mechanism in which friction devices are employed engaging with the surface of the roll for controlling the rotation thereof.

In this class of mechanism, certain friction devices are provided which engage the surface of the unwinding web roll and act to control the rotation of the roll so that the web is fed into the press under the desired tension. These web rolls as they unwind, of course, decrease in size and, as they decrease in size, the pressure produced by the friction devices must vary, it being desirable to increase this pressure as the unwinding roll decreases in size and, where the roll is materially decreased in size, it is desirable to cause a considerable increase in the pressure applied to the surface of the roll. Where, as is frequently the case in this class of mechanism, the friction devices are in the form of belts, it is desirable that the belts be of such size and so arranged as to engage the roll surface at points which form the margin spaces of the web after printing so as to prevent as far as possible the formation of lint, which is undesirable, in that it leads to bad printing.

It is the especial object of the present invention to produce an improved arrangement of friction controlling devices for controlling the unwinding roll during its unwinding, and additional friction devices normally out of contact with the roll but which may be caused to engage with the roll when the roll has unwound to the point at which additional pressure on the roll is necessary or desirable, so that the increase in pressure on the roll surface may be easily and readily obtained.

A further object of the present invention is to arrange these additional friction devices so that they will engage the roll at the points which will form the margin spaces of the web after printing, so as to avoid as far

as possible roughing up the surface of the web and the consequent formation of lint.

With these and other objects not specifically referred to, the invention consists in certain novel parts, arrangements and combinations which will be described in connection with the accompanying drawings and the novel features pointed out in the claims hereunto appended.

In these drawings,—

Figure 1 is an end view of a web roll controlling mechanism embodying the invention, the view being partly diagrammatic and partly in section;

Figure 2 is a view similar to Fig. 1 showing the parts in a different position and the auxiliary friction devices engaging the unwinding roll;

Figure 3 is a front view of the construction shown in Figs. 1 and 2 showing one arrangement of the auxiliary friction devices when these are arranged to engage the roll in the margin spaces; and

Figure 4 is a view similar to Fig. 3 showing a modified arrangement of the auxiliary friction devices.

Referring now to these drawings, the mechanism which has been selected to illustrate the invention is a roll changer capacitated to carry a running web roll and a spare web roll, the support for the roll being capable of being rotated, but it will be understood that the invention, as to certain of its features, may be used in other relations and with other forms of web roll support.

In the particular mechanism shown, there is provided a roll support including a pair of spaced arms 1, 2, each arm being provided with bearings 3, 4 preferably diametrically arranged for supporting the journals of a running web roll marked R and a spare web roll marked S. These arms 1, 2 are mounted so that they may have a rotary movement, each arm being provided with a hub 5 mounted on a shaft 6 suitably supported in the ma-

chine, there being driving mechanism for rotating this shaft, not shown, it being unnecessary for an understanding of the invention. The web W from the unwinding roll passes over the guide roll 7 to the press, not shown.

In accordance with the invention, this unwinding web is controlled by certain friction devices which, while they may assume various forms, are illustrated as being narrow belts or straps of any suitable material, such as canvas or leather, three such straps 8, 9 and 10 being illustrated. These belts are arranged side by side and, in the best constructions, engage the roll surface at points which become the margin spaces after the web is printed, the arrangement shown being one for printing a four page wide product. These belts may be mounted and supported in various ways. In the particular construction shown, the belts are free at one end, being carried over a suitable roll 11, and having secured at their free ends weights 12, so that as the roll decreases in size the weights will drop and take up the slack of the belts, thus keeping the belts under the desired tension.

The belts at their other ends are secured around a rod 13 mounted in lever arms 14 pivoted on a shaft 15, the other arms 16 of these levers being connected to a spring, not shown. These belts engage the roll surface and act to maintain a pressure on the roll while it is unwinding, thus providing the required tension for the unwinding web. Under some circumstances and particularly when the roll materially decreases in size, greater tension on the web is required than can be conveniently given it with these belts and, in accordance with the invention, additional tension devices are provided which may be caused to engage the roll surface so as to produce the required additional pressure. While these auxiliary or additional friction devices may be of various characters and while their engagement with the roll surface may be effected in various ways, in the preferred embodiment of the invention, these additional friction devices will be belts or straps which normally are positioned out of contact with the roll and are brought into contact with the roll by rotating the roll support so as to bring the roll into engagement with these additional belts. These belts, of course, may be provided in any desired number, and arranged as may be desired.

In the particular construction shown, referring first to Fig. 3, there are provided three of these additional straps, marked 17, 18 and 19, these being broken, as shown, for clarity of illustration, and these straps are arranged so as to bear against the straps 8, 9, and 10, before referred to. Thus the additional friction devices lie over the regular friction belts and thus are in the margin spaces formed in the web after printing.

As shown, the straps 8, 9 and 10 pass over a guide roll 20 which positions them in the desired relation to the web roll. The auxiliary straps also pass over the roll 11 and are also provided with weights 21 at their free ends. In Fig. 4 is illustrated a slight modification of the arrangement of the belts. As shown in this figure, there are but two auxiliary belts 22, 23 which occupy positions between the belts 8, 9 and 10, this construction being advantageous under some circumstances. These auxiliary belts, it will be observed, are narrow belts and, as they are in contact with the roll surface but a comparatively short time, their engagement with the roll surface does not rough up the surface sufficiently to cause an undesirable formation of lint.

The operation of the web controlling mechanism may be briefly described as follows: In the ordinary running position, as shown in Fig. 1, the belts 8, 9 and 10 engage the surface of the running web roll R and the auxiliary belts are not brought into contact with the roll. When now the roll is materially decreased in size, the roll support is rotated so as to bring the running web R into the position shown in Fig. 2. When this has been done, it will be observed, that the auxiliary belts are brought into engagement with either the belts 8, 9 and 10 or with the roll surface between the belts, depending on which arrangement is used, and the additional pressure is supplied to the running roll. It will be observed that the lap or the contact area of the auxiliary belts with the roll may be determined by the amount of rotary movement given the roll support so that the pressure of the belts on the roll may be nicely adjusted.

While the invention has been shown and described in its preferred form, it will be understood that various changes may be made in the structure shown and described, and the invention, therefore, is not to be limited to the exact structure and arrangement of the parts shown.

What I claim is:

1. In a web roll controlling mechanism for printing machines, the combination of friction devices engaging the roll surface for controlling the tension of the unwinding roll, and auxiliary friction devices normally out of contact with the roll, but arranged for operative relation with the roll for supplying additional pressure to the surface of the roll that varies in circumference as the roll unwinds.

2. In a web roll controlling mechanism for printing machines, the combination of friction belts engaging the roll surface for controlling the tension of the unwinding roll, and auxiliary friction belts normally out of contact with the roll, but arranged for oper-

ative relation with the roll for supplying additional pressure to the unwinding roll.

3. In a web roll controlling mechanism for printing machines, the combination of a movable web roll support, friction devices engaging the roll surface for controlling the tension of the unwinding roll, and auxiliary friction devices normally out of contact with the roll and brought into operative relation therewith by moving the support for supplying additional pressure to the unwinding roll.

4. In a web roll controlling mechanism for printing machines, the combination of a rotary web roll support, friction belts engaging the roll surface for controlling the tension of the unwinding roll, and auxiliary friction belts normally out of contact with the roll, but brought into operative relation with the roll surface by rotating the roll support, for supplying additional pressure to the unwinding roll.

5. In a web roll controlling mechanism for printing machines, the combination of friction devices engaging the roll surface for controlling the tension of the unwinding roll, and auxiliary friction devices normally out of contact with the roll, but arranged for engagement with the first named friction devices for supplying additional pressure to the unwinding roll.

6. In a web roll controlling mechanism for printing machines, the combination of narrow friction belts engaging the roll surface for controlling the tension of the unwinding roll and arranged in the margin spaces of the web, and auxiliary friction belts normally out of contact with the roll, but arranged for engagement with the narrow belts for supplying additional pressure to the unwinding roll.

7. In a web roll controlling mechanism for printing machines, the combination of friction belts engaging the roll surface for controlling the tension of the unwinding roll, said belts being secured at one end and free at the other, weights at the free end of the belts, and auxiliary belts secured at one end and free at the other with weights at the free end normally out of contact with the roll, but arranged for operative relation with the roll for supplying additional pressure to the unwinding roll.

8. In a web roll controlling mechanism for printing machines, the combination of a rotary web roll support, friction belts engaging the roll surface for controlling the tension of the unwinding roll, said belts being secured at one end and free at the other, and auxiliary belts secured at one end and free at the other normally out of contact with the roll, but arranged for operative relation with the roll by rotating the support for supplying additional pressure to the unwinding roll.

9. In a web roll controlling mechanism for

printing machines, the combination of friction devices engaging the roll surface for controlling the tension of the unwinding roll, and auxiliary friction devices normally out of contact with the roll, but arranged for operative relation with the roll between its ends for supplying additional pressure to the unwinding roll.

In testimony whereof, I have hereunto set my hand.

WALTER H. OGDEN.
